United States Patent Office.

JAMES P. DAVIS, OF STILES, WISCONSIN.

Letters Patent No. 77,464, dated May 5, 1868.

IMPROVEMENT IN MECHANICAL MOVEMENT.

The Schedule referred to in these Letters Patent and making part of the same.

TO ALL WHOM IT MAY CONCERN:

Be it known that I, JAMES P. DAVIS, of Stiles, in the county of Oconto, and State of Wisconsin, have invented a new and useful Improvement in Mechanical Movement; and I do hereby declare that the following is a full, clear, and exact description thereof, which will enable those skilled in the art to make and use the same, reference being had to the accompanying drawings, forming part of this specification.

Figure 1 is a sectional elevation of my improvement.

Figure 2 is a cross-section of the same through the line $z z$, fig. 1.

Figure 3 is a detail view of the gearing.

Figure 4 is a diagram exhibiting the position of the friction-wheels at the end of the stroke.

Figure 5 is a detail diagram, exhibiting the manner of connecting the crank-shaft with the main shaft.

Similar letters of reference indicate corresponding parts.

This invention relates to certain devices for the purpose of converting rectilinear into rotary motion without employing a crank upon the main shaft.

It consists in the mechanism now to be set forth.

In the drawings, A is the bed-plate supporting the fly-wheel bearings and frame B, which latter furnishes the bearings for the friction-wheels D and loose pulleys E. The cross-head F works with close contact with and between the friction-pulleys D; the loose pulleys E being also in contact with the cross-head, as shown. The upper and lower surfaces of the cross-head are slotted, to receive the adjustable friction-racks a , which are raised or lowered by the set-screws b , whereby the said racks are brought to bear upon the friction-pulleys with the proper degree of contact for transmitting its rectilinear motion to them. Gear-wheels G G are mounted rigidly on the shafts d of the friction-pulleys, and exterior to the frame B, as shown. These wheels engage with a middle wheel, H, keyed on the shaft d' , which is properly the main driving-shaft, which latter is to be connected with the machinery to be driven. These three gear-wheels have equal diameters. The loose pulleys E are for the purpose of holding the cross-head firmly, and thereby prevent its springing. The semi-circumferences of the friction-pulleys are equal to the stroke of the piston. One-half of the periphery of each friction-pulley, as from e to e' , is recessed or cut away lower than the remainder, for the purpose of relieving the said pulleys from contact with the racks on the cross-head at the completion of the stroke of the latter.

The friction-surfaces m impinge alternately against upper and lower friction-racks respectively, when the cross-head is actuated to and fro by the stroke of the piston. The friction-surfaces of the friction-pulleys are made slightly less than a semi-circumference by the short recess i , which is made for the purpose of enabling the friction-surface of one pulley to pass from contact with its friction-rack just the instant before that of the opposite pulley comes in contact with its respective rack at the return-stroke of the cross-head. By the reciprocal motion of the cross-head, the friction-surfaces of the friction-pulleys impinge alternately upon the friction-racks, and are thereby actuated in one direction only, for at the completion of the stroke in either direction, one of the pulleys passes from contact with the cross-head, by means of the recess before mentioned, and would remain at rest while the cross-head completed the contrary stroke, if not forced to continue its rotation by the middle gear-wheel H, which is driven by the gear-wheel G or G' on the shaft of the friction-pulley, that took motion from the cross-head just as the other passed from contact.

To insure the regular and certain action of the friction-pulleys, a single cog or projection, n , is affixed to the end of each friction-rack, and comes in contact with the shoulder c' , as shown at fig. 4, just before the completion of the stroke, and, with a positive motion, carries the friction-surface clear of the rack by bringing the short recess i at the lowest point of the pulley. The cross-head is then relieved from contact with the friction-surface of the other on the return stroke. This action takes place at each end of the stroke, for the continued revolution of the friction-pulleys brings the friction-surfaces, shoulders, and recesses, back to the proper position for repeating the movement at each stroke of the piston.

In practice, a pulley, I, is keyed on the main shaft d' , and a belt, h , connects the main shaft with the crank-shaft and fly-wheel, as shown at figs. 1 and 5.

The crank limits the motion of the cross-head, and the connection of the crank-shaft and main shaft steadies the motion, thereby preventing any backlash of the gearing, and conduces to the regular and respondent action of the whole mechanism.

My invention is simple and efficient, and has been proven, by experimental trial, to produce a rotary motion from a rectilinear motion in a highly satisfactory manner.

I claim as new, and desire to secure by Letters Patent—

1. The recessed friction-pulleys D and racks a , operating substantially as shown and described, and for the purpose specified.

2. The gear-wheels G G' H, substantially as shown and described, in combination with the friction-pulleys D D, as and for the purpose set forth.

3. The pulley I, belt h , and fly-wheel, substantially as shown and described, in combination with the recessed friction-pulleys D and cross-head F, for the purpose of accomplishing the more perfect working of the parts, all as set forth.

4. The cross-head F, cogs n , friction-racks a , substantially as shown and described, in combination with the friction-pulleys D, all as and for the purpose set forth.

The above specification of my invention signed by me, this 30th day of November, 1867.

JAMES P. DAVIS.
